DESIGN FOR A DRESS

David Goldenberg, New York, N. Y.

Application February 23, 1938, Serial No. 75,344

Term of patent 3½ years

To all whom it may concern:

Be it known that I, David Goldenberg, a citizen of the United States of America, residing in city of New York, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

The characteristic feature of my design resides in the combination on the specific dress disclosed of the pleated panels extending from the yoke to the waistline on the blouse portion and the pleated panels on the attached skirt panel extending from the hipline to a point below the hemline as shown.

I claim:

The ornamental design for a dress substantially as shown and described.

DAVID GOLDENBERG.
